TILLER FRAME AND SUPPORT

Mando S. Ariens, Brillion, Wis.

Application September 23, 1944, Serial No. 555,513

3 Claims. (Cl. 97—40)

1

This invention appertains to rotary tillers and soil pulverizers of the type shown in my Patent 2,025,494, issued December 24, 1935, and more particularly to a novel means for mounting the tiller on a supporting frame and is an improvement on my Patent 2,347,017, issued April 18, 1944.

One of the primary objects of my invention is to provide a fixed land roller supported frame, so as to prevent swaying or tilting of the frame with novel means for hingedly mounting the tiller in the frame, whereby the tiller can conveniently be raised or lowered on the frame through a suitable mechanism, such as a hydraulic lift device.

Another salient object of my invention is to provide means for not only hingedly mounting the tiller on the frame, but for also resiliently suspending the tiller, so that said tiller will be free to give if the tines encounter solid objects whereby injury to the tiller will be prevented.

A further important object of my invention is the provision of novel means for mounting the rotary tiller on the frame in such a manner that the resilient supporting means therefore will not interfere with the operation of the hydraulic lift mechanism.

A still further important object of my invention is to provide an improved mounting for my rotary tiller, which will be strong and rugged in use and one that can be manufactured and placed upon the market at a reasonable cost.

With these and other objects in view, the invention consists in the novel construction, arrangement and formation of parts as will be hereinafter more specifically described, claimed and illustrated in the accompanying drawings, in which drawings:

Figure 1 is a side elevational view of my improved device with parts thereof broken away and in section to illustrate structural detail.

Figure 2 is a top plan view of my improved frame and supporting structure.

Figure 3 is an enlarged fragmentary transverse sectional view through the device taken on the line 3—3 of Figure 1 looking in the direction of the arrows, showing my novel mounting.

Figure 4 is a similar sectional view with the section taken on the line 4—4 of Figure 1 looking in the direction of the arrows.

Referring to the drawings in detail, wherein similar reference characters designate corresponding parts throughout the several views, the letter M generally indicates my improved machine and the same includes a rigid or fixed supporting frame F in which is mounted the rotary

2

tiller or soil pulverizer T. The rotary soil pulverizer T is mounted within the frame by my novel supporting mechanism S.

The rotary tiller T can be of the same type and character as shown in my Patent 2,025,494 and hence the same includes the rotary earth working element 5 carrying a plurality of resilient tines 6. The member 5 is rotated through the medium of a drive shaft 7 from the power take off of a pulling tractor (not shown).

My novel frame F includes a pair of spaced parallel frame beams 8 and 9, which can be formed from channel iron, if so desired. The rear ends of the beams 8 and 9 are rigidly connected together by a rear cross beam 10. The forward terminals of the side beams 8 and 9 are inclined inwardly toward one another and the longitudinal center of the frame as at 11 and these beams terminate at a forwardly projecting draft beam 12. The forward end of the draft beam 12 carries a coupling 13 so that the machine can be attached to a tractor and I prefer to use that type of coupling shown in my Patent 2,347,017.

The frame F also includes a front transversely extending cross beam 14, which is rigidly fastened to the side frame beams 8 and 9. Rigidly fastened to the cross beam 14 is an upright frame plate 15 and this plate is firmly braced by struts 16 which extend from the plate forwardly into engagement with the forward ends of the side beams. Formed on or rigidly fastened to the upper corners of the plate 15 are rearwardly projecting pivot lugs or wings 17 and these lugs or wings form the support for the transversely extending pivot shaft 18. The plate 15, the lugs 17 and the shaft 18 all form a part of my novel support S for the tiller T.

The support S also includes a pair of spaced parallel rigid frame plates 19 which are securely welded or otherwise fastened to the front of the tiller T and these frame plates 19 form a direct part of said tiller and project forwardly therefrom toward the upright plate 15. Disposed between the rigid frame plates 19 are a pair of spaced parallel triangular shaped connecting plates 20. The plates 20 are firmly united together by an upper cross rod 21, the terminals of which are rigidly fastened to said connecting plates. The lower rear corners of the plates 20 are rockably mounted upon a cross pivot shaft 22, which is carried by the lower ends of the rigid frame plates 19. The forward upper corners of the connecting plates 20 are rockably mounted upon the cross or pivot shaft 18.

In order to provide the resilient mounting or support for the tiller the rigid frame plates have

rockably mounted on pivot pins 23 carried thereby forwardly projecting supporting bolts 24. These bolts slidably extend through guide openings formed in guide ears 25 rigidly fastened to the outer faces of the connecting plates 20. Expansion springs 26 are coiled about the bolts 24 and their rear ends engage and rest up against the ears 25. Adjustable nuts 27 mounted on the bolts 24 engage and confine the outer ends of the springs 26. The bolts 24 are arranged above the cross shaft 22 and swinging movement of the tiller T on the cross shaft 22 is limited and arrested by the springs 26.

In order to permit the convenient raising and lowering of the tiller T on the frame F I provide an hydraulic lift. This mechanism includes a cylinder 28, the inner end of which is rockably mounted on the front transverse cross beam 14, as at 29. Mounted for reciprocatory movement in the cylinder 28 is a piston (not shown) carrying a rearwardly extending piston rod 30 and the rear end of this piston rod is rockably mounted upon the cross shaft 22. The hydraulic lift mechanism is of a type which can be purchased in the open market and forms no part of the invention per se and hence the same is not described in detail. However, flow of fluid to the opposite ends of the cylinder controls the direction of movement of the piston and the consequent raising and lowering of the tiller in the frame. It being obvious that the tiller will swing on the shaft 18 when the hydraulic lift mechanism is actuated. The control valve mechanism for the cylinder can be located on the tractor within convenient reach of the operator.

While I have stated that the tiller is lifted through a suitable hydraulic mechanism, it is to be understood that a mechanical raising and lowering mechanism can be employed.

The rear end of the frame F is supported by a transverse extending land roller 31. This land roller extends entirely across the machine in the same manner as shown in my Patent No. 2,347,017 and the ends of the shaft for the roller are mounted in suitable bearings carried by the beams 8 and 9. Attention is called to the fact, however, that the land roller 31 is corrugated to provide a series of annular ribs, which are of a V-shape in cross section.

From the foregoing description, it can be seen that I have provided a simple but sturdy means for resiliently and hingedly supporting the tiller T within a rigid or fixed land supported frame.

Changes in details may be made without departing from the spirit or the scope of my invention, but what I claim as new is:

1. In a machine for working, leveling and packing soil in one operation, a rigid frame including spaced parallel side beams, a rotary land roller carried by the rear end of the frame and rotatably supported on the side beams, a coupling member for connection with a tractor carried by

the front of the frame, and a rigid transversely extending upright supporting member secured to the frame, a rotary tiller mounted between said side beams between the land roller and the coupling member, forwardly extending spaced parallel frame plates carried by the rotary tiller, connecting plates rockably mounted at their lower ends on said spaced plates, means hingedly mounting the connecting plates to the upper end of the upright member, a resilient connection between the pair of frame plates and the connecting plates, and a hydraulic lift mechanism between the frame and the tiller.

2. In a machine for working, leveling and packing soil in one operation, a rigid frame including spaced parallel side beams, a rotary land roller carried by the rear end of the frame and rotatably supported on the side beams, a coupling member for connection with a tractor carried by the front of the frame, and a rigid transversely extending upright supporting member secured to the frame, a rotary tiller mounted between said side beams between the land roller and the coupling member, forwardly extending spaced parallel frame plates carried by the rotary tiller, connecting plates rockably mounted at their lower ends on said spaced plates, means hingedly mounting the connecting plates to the upper end of the upright member, a resilient connection between the pair of frame plates and the connecting plates, and a hydraulic lift mechanism between the frame and the tiller; said hydraulic lift mechanism being disposed below the resilient connection and the pivotal connection of the connecting plates with the upright member.

3. In a machine for working, leveling and packing soil in one operation, a rigid frame including spaced parallel side beams, a transversely extending land roller supporting the rear end of the frame, a coupling member carried by the front end of the frame, a rotary tiller disposed between the side beams and between the land roller and the coupling member, an upright supporting member on the frame, spaced frame plates rigidly secured to the front end of the tiller, a pair of forwardly extending connecting plates, a cross rod rockably mounting the lower ends of the connecting plates on the lower ends of the forwardly projecting frame plates, a pivot shaft rockably connecting the forward upper ends of the connecting plates to the upright member, spring bolts pivotally connected to the frame plates and slidably connected with the connecting plates, expansion springs on said bolts engaging the connecting plates, adjustable members on said bolts engaging the forward ends of the springs, and a hydraulic lift mechanism for the rotary tiller including a cylinder pivotally connected to the upright supporting member and a piston in said cylinder rockably connected to the cross rod.

MANDO S. ARIENS.
